(57) **CLAIM**

The ornamental design for a flame shelf, as shown and described.

DESCRIPTION

FIG. 1 is a perspective view showing my new design.

FIG. 2 is a front view thereof.

FIG. 3 is a right end view thereof and it is a mirror image of the left end.

FIG. 4 is a top view thereof.

FIG. 5 is a bottom view thereof; and,

FIG. 6 is a rear view thereof.

The design features unique three dimensional flames in a shelf design.
